Patented Dec. 16, 1919.

UNITED STATES PATENT OFFICE.

GEORGE BEY, OF NEWARK, NEW JERSEY.

CUE.

1,324,789.

Specification of Letters Patent. Patented Dec. 16, 1919.

Application filed July 18, 1919. Serial No. 311,830.

To all whom it may concern:

Be it known that I, GEORGE BEY, a citizen of the United States, and a resident of Newark, county of Essex, and State of New Jersey, have invented certain new and useful Improvements in Cues, of which the following is a specification.

This invention relates to an improved cue for use in playing billiards, pool and like games, and is designed to provide a cue that is wielded as an ordinary cue, but has a grip that is movable relative to the cue provided to enable more accurate shooting and to assist in drawing the cue ball.

15 It is sometimes necessary to draw the cue ball, that is, make it roll backward after it hits the object ball, this being done by hitting the cue ball below the center, and sometimes it is necessary to draw the cue ball 20 and at the same time hit it lightly, and a few very experienced players can draw the ball when the cue ball travels but a short distance, or if it is hit lightly the wrist motion 25 of the player being utilized in the manipulation of the cue.

My invention makes it possible to more effectively draw the cue ball by reason of the grip having a yielding connection with the cue, so that when the tip of the cue hits 30 the cue ball it loses its full force for the reason that the grip is advanced slightly along the cue and the tendency of reverse rotation of the ball is not destroyed by excessive forward movement of the cue after 35 the cue contacts with the cue ball.

A further object of the invention is to provide a cue of this kind in which the tension of the yielding means, such as a spring, can be regulated according to the wishes of the 40 player.

The invention is illustrated in the accompanying drawing, in which Figure 1 is a side view of a cue provided with my improved grip. Fig. 2 is an enlarged detail 45 view showing the cue partly broken away and with the grip in section, and Fig. 3 is a section on line 3—3 in Fig. 2.

The cue 10 is of any usual form and is provided at the end with a tip 11, which is 50 usually made of leather and used for striking the cue ball. The handle portion 12 of the cue is provided with a suitable grip 13, which may be of various forms, but is preferably made of a tubular sleeve that fits 55 around the outside of the cue and is slidably longitudinally thereon without undue fric-

tion, so that its movement is not restricted or impeded by any tight fit between the cue and the grip.

The grip 13 is held so that it yields, that 60 is, it can move forward under a slight tension on the cue. In other words, the cue can retreat within the grip, being held in normal position by a yielding means. The means illustrated in the drawing is a spring 65 14, which, in order to make the device compact, is seated in a groove 15 in the cue and is fastened at one end, as at 16, to the sleeve, and at the other end, as at 17, to the cue.

It will thus be seen that when the cue is 70 handled by the player and the cue is used to hit the cue ball, when the tip 11 contacts with the cue ball the resistance that the ball offers to the cue causes the cue to be relieved of the pressure of the hand, to which it 75 would otherwise be subjected, and the yielding means, such as the spring 14, comes into play.

With a light shot it will thus be seen that the cue does not drive the cue ball positively 80 forward to overcome the reverse twist by means of which the cue ball is drawn, and I am enabled by this cue to tap the cue ball but lightly and still be able to draw the cue ball to an extent much greater than is possible 85 with the ordinary cue.

The initial or normal pressure of the spring can be regulated by an adjustment to position the grip on the cue. One form of such regulation is by a pin 18, which fits 90 tightly into any of the series of holes 19, spaced apart as desired, the pin 18 projecting sufficiently to permit its engagement with the back edge of the sleeve 13, but not projecting to an extent great enough to cause 95 it to interfere with the natural handling of the cue.

The pin 18 fits tightly into the hole, one way of doing this being to split the pin, as at 20. It will be evident that if the pin is 100 placed in one of the holes nearest the end 17 of the spring, the spring will be under a light tension, whereas if it is more advanced, that is, placed forward beyond this point, the tension of the spring will be increased. 105 This adjustment can also be used for taking up any weakness that might be developed in the spring through long use.

The particular arrangement of the parts as illustrated is not essential to the invention, and the parts can be arranged differently relative to one another, and they can 110

be of modified shapes, without departing from the scope of the invention.

I claim:

1. A cue having a comparatively small shell-like grip thereon, which grip has a limited longitudinal sliding movement on the cue.
2. A cue having a relatively small grip slidable longitudinally thereon, and a connection connecting the cue and grip to yieldingly hold the grip in its normal position.
3. A cue having a grip slidable longitudinally thereon, a connection connecting the cue and grip to yieldingly hold the grip in its normal position, and a stop for limiting the movement of the grip.
4. A cue having a grip slidable longitudinally thereon, a spring connecting the grip and the cue to hold the grip in its normal position, and a stop for the grip to prevent rearward movement of the grip beyond the normal.
5. A cue having a grip slidable longitudinally thereon, a spring connecting the cue

and the grip to permit rearward movement 25 of the cue in the grip, and a stop for limiting the forward movement of the cue in the grip.

6. A cue having a grip slidable longitudinally thereon, a spring connecting the cue 30 and the grip to permit rearward movement of the cue in the grip, and an adjustable stop for engaging the cue and the grip and limiting the forward movement of the cue in the grip.

7. A cue having a tubular grip slidable longitudinally thereon, a groove in the cue, a spring in the groove and attached to the cue and the grip, and a stop adjustable on the cue for engaging the grip for limiting 40 the forward movement of the cue in the grip and regulating the normal tension of the spring.

In testimony that I claim the foregoing, I have hereto set my hand, this 16th day of 45 July, 1919.

GEORGE BEY.
